ABSTRACT OF THE DISCLOSURE

A control system is provided for energizing and de-energizing the relays in a relay matrix. The matrix consists of a plurality of groups of relays. Each relay group has a common marking conductor. A control circuit is provided having two control conductors for each relay of a relay group, with each pair of control conductors corresponding to a separate relay from each group. Each relay is connected in control circuit that permits it to be held by its own contact through either the corresponding marking conductor or one of the corresponding control conductors, and to be energized by marking the corresponding marking conductor and the other corresponding control conductor.

The invention relates to a system comprising a number of relay arrangements which each have a number of relays each of which is provided with at least one winding and several relay contacts, which system further comprises a marking arrangement having one marking conductor for each relay arrangement, whilst for selecting a given relay arrangement, the corresponding marking conductor is provided with a mark from the marking arrangement, the system further comprising a control arrangement common to all the relay arrangements which for each relay in an arbitrary relay arrangement is provided with two control conductors, each control conductor being common to a number of relays associated with different relay arrangements.

Such a system of relay arrangements is used inter alia in automatic telephone exchanges which are centrally controlled. An example is the control of the repeaters coupling the internal connection lines with the external connection lines, which repeaters each include a number of relays having various functions.

The invention has for its object to provide a new construction of the system mentioned in the preamble by which a considerable saving in apparatus can be obtained.

The system in accordance with the invention is characterized in that each marking conductor is multiple-connected in the associated relay arrangement to first branch points added to each of the relays through decoupling rectifiers added to each of the branch points, in that an energizing winding of each relay is connected between the associated first branch point and a further branch point connected through a decoupling rectifier to a control conductor and in that a holding winding of each relay is connected between the associated second branch point connected through a decoupling rectifier to a control conductor and a third branch point connected through a make contact of the relay to a point of constant potential, the first branch point of each relay being connected with a resistor the other end of which is adapted to receive a switching-on potential.

The invention and its advantages will now be described more fully with reference to an embodiment shown in the sole figure.

2

The figure shows two relay arrangements W_1 and W_2 of a number of such arrangements that can be chosen arbitrarily in practice. These relay arrangements are, for example, the repeaters of an automatic telephone exchange. Each relay arrangement comprises several relays which are each provided with one winding and with several make contacts, for example, so-called magnet tongue relays (reed-type relays). The figure shows the windings of three relays of each relay arrangement and one make contact of each relay. In the arrangement W_1 , the windings of the relays K_{11} , K_{12} and K_{13} and the associated contacts k_{11} , k_{12} and k_{13} are shown and in the arrangement W_2 , the windings of the relays K_{21} , K_{22} and K_{23} and the associated contacts k_{21} , k_{22} and k_{23} are shown. These windings are each included in a circuit, referred to hereinafter as control circuit, which is denoted by T . The control circuits are distinguished from each other by two indices the first of which is the same as that of the relay arrangement and the second of which designates the ordinal numeral in the arrangement. The control circuits are identical so that the description of one control circuit is sufficient. By way of example, the control circuit T_{11} will be described. The figure further shows a marking arrangement M and a common control arrangement SS . The marking arrangement M comprises a number of marking conductors equal to the number of relay arrangements and in this case it comprises the marking conductor M_1 associated with the arrangement W_1 and a marking conductor M_2 associated with the arrangement W_2 . Normally, the marking conductors are connected to earth through associated marking contacts m_1 and m_2 , respectively. The common control arrangement SS comprises a number of pairs of control conductors equal to the number of relays in the relay arrangements and in this case it comprises the control conductors U_1 and V_1 associated with the control circuits bearing the ordinal numeral 1, the control conductors U_2 and V_2 associated with the control circuits bearing the ordinal numeral 2, and the control conductors U_3 and V_3 associated with the control circuits bearing the ordinal numeral 3. The control conductors V_1 , V_2 and V_3 , referred to hereinafter as first control conductors, are normally each connected to earth through an associated control contact v_1 , v_2 and v_3 and the control conductors U_1 , U_2 and U_3 , referred to hereinafter as second control conductors, can be each connected through an associated control contact u_1 , u_2 and u_3 to a point of negative potential. The control circuit T_{11} will now be described more fully. The marking conductor M_1 associated with the arrangement W_1 is connected through a marking conductor $1M_1$ and a rectifier $4D_{11}$ to a branch point 1 of a resistor $1R_{11}$ and a rectifier $3D_{11}$. The other end of resistor $1R_{11}$ is connected to the control conductor U_1 . The pass direction of rectifier $4D_{11}$ is chosen so that if the marking conductor M_1 is at earth potential and the control conductor U_1 is at a negative potential, the rectifier conveys a current and the branch point 1 is held at earth potential. The other end of rectifier $3D_{11}$ is connected to a branch point 2 of winding K_{11} and make contact k_{11} . The other end of the contact k_{11} is connected through a resistor $2R_{11}$ to a point of negative potential. The other end of winding K_{11} is connected to a branch point 3 of the rectifiers $1D_{11}$ and $2D_{11}$. The other end of rectifier $1D_{11}$ is connected to the control conductor V_1 and the other end of rectifier $2D_{11}$ is connected through marking conductor $2M_1$ to marking conductor M_1 . The pass directions of rectifiers $1D_{11}$, $2D_{11}$ and $3D_{11}$ are equal and are chosen so that if control conductor V_1 or marking conductor M_1 is at earth potential, the rectifier $1D_{11}$ or rectifier $2D_{11}$ conveys a current through winding K_{11} and rectifier $3D_{11}$ to branch point 1 if the latter is at earth potential or through winding K_{11} , make contact

k_{11} and resistor $2R_{11}$ to a point of negative potential if the contact k_{11} is closed. The control circuits T_{12} and T_{13} are connected in the same manner to the marking conductors $1M_1$ and $2M_1$ as control circuit T_{11} and the connection with the control conductors U_2 and V_2 and U_3 and V_3 , respectively, is also established in quite the same manner. In the arrangement W_2 , the control circuits T_{21} , T_{22} and T_{23} are connected in the same manner to the marking conductors $1M_2$ and $2M_2$ and the connection with the control conductors is also established in an analogous manner. The rectifiers in the control circuits decouple completely the control circuits connected to the same marking and control conductors.

In order to switch on a relay in a relay arrangement, the relevant marking conductor in the marking arrangement M is disconnected from earth and the relevant second control conductor in the common control arrangement SS is connected to a point of negative potential. The example considered is the relay K_{11} in the arrangement W_1 . In the marking arrangement M , the marking contact m_1 is opened and in the common control arrangement SS , the control contact u_1 is closed. Thus, the following energizing current circuit is obtained: negative potential, contact u_1 , conductor U_1 , resistor $1R_{11}$, rectifier $3D_{11}$, winding K_{11} , rectifier $1D_{11}$, conductor V_1 , contact v_1 , earth. An energizing current flows through this energizing current circuit so that the contact k_{11} is closed. The contact k_{11} directly connects the branch point 2 through a resistor $2R_{11}$ to a point of negative potential so that the relay continues to be held after the control contact u_1 has been opened. The following holding-current circuit is obtained: earth, contact v_1 , conductor V_1 , rectifier $1D_{11}$, winding K_{11} , contact k_{11} , resistor $2R_{11}$, negative potential. After the marking contact m_1 has been closed, an alternative holding-current circuit is obtained: earth, contact m_1 , conductor M_1 , conductor $2M_1$, rectifier $2D_{11}$ and then through the first-mentioned holding-current circuit to negative potential. If after the energization of relay K_{11} , first the contact m_1 is closed and then the contact u_1 is opened, the relay K_{11} is first held through the alternative holding-current circuit and then through both holding-current circuits. The said energizing-current circuit is obtained due to the fact that the marking conductor M_1 is disconnected from earth. In the opposite case in which the marking conductor M_1 is connected to earth when the control contact u_1 is closed, a current starts flowing through the rectifier $4D_{11}$, which current holds the branch point 1 at earth potential. If the relay K_{11} is not energized, both ends of the winding K_{11} are at earth potential and the state of the relay remains unchanged. In case the relay K_{11} is energized and is held through make contact k_{11} , rectifier $3D_{11}$ is blocked by the earth potential at branch point 1 for the negative potential at branch point 2 and the relay K_{11} continues to be held. If during the energization of relay K_{11} , other relays of the arrangement W_1 are also energized, the latter continue to be held through the associated first control conductors which are connected to earth in the common control arrangement SS .

When a relay in a relay arrangement is switched off, which is again described with reference to relay K_{11} of the arrangement W_1 , the marking contact m_1 of the marking arrangement M is opened and the control contact v_1 in the common arrangement SS is also opened. As a result, both the holding-current circuit through control conductor V_1 and the alternative holding-current circuit through marking conductor M_1 are interrupted so that the relay K_{11} is de-energized. If beside the relay K_{11} , other relays of the arrangement W_1 are energized, like in the case in which the relay K_{11} is switched on, these relays continue to be held through the associated first control conductors which are connected to earth in the common control arrangement SS . If among the relays the control circuits of which are connected to control conductor V_1 beside relay K_{11} also other relays are energized, the latter continue to be held through the associated marking conductors

which are connected to earth in the marking arrangement M .

In the apparatus described above, it is of importance that each relay arrangement requires only one marking contact which is operative in the associated relay arrangement both when a relay is switched on and when a relay is switched off. Thus, the marking apparatus required for marking the relay arrangements is reduced substantially by half. This saving is due to the double function of the marking contacts. Each marking contact acts as a blocking contact preventing a relay in the associated relay arrangement from being switched on and as a holding contact for the relays which have been energized so that an energized relay is prevented from being switched off. When the marking contact is opened, both the prohibition for switching on a relay and the prohibition for switching off a relay are eliminated and the common control arrangement SS can bring about a desired change of state (switching-on or switching-off) in the marked relay arrangement. For the sake of clarity, it should be noted that, if after a relay has been switched on, the relevant marking contact is closed before the negative potential of the relevant second control conductor is neutralized, the energizing-current circuit is interrupted by the earth potential at branch point 1, while at the same time a holding-current circuit is formed through the same marking contact that brings about the potential variation at branch point 1. The double function of the marking contact now becomes clearly manifest.

What is claimed is:

1. A system comprising a number of relay arrangements which each have a number of relays each provided with at least one winding and with several relay contacts, which system further comprises a marking arrangement having for each relay arrangement one marking conductor, whilst for selecting a given relay arrangement, the corresponding marking conductor is provided with a mark from the marking arrangement, the system further comprising a control arrangement which is not common to all the relay arrangements and which for each relay is an arbitrary relay arrangement is provided with two control conductors each of which is common to a number of relays associated with different relay arrangements, characterized in that each marking conductor (M_1) is multi-connected in the associated relay arrangement (W_1) to first and second branch points (1 and 3 respectively) added to each of the relays (K_{11}) through decoupling rectifiers ($4D_{11}$ and $2D_{11}$ respectively) added to each of the branch points, in that an energizing winding of each relay (K_{11}) is connected between the associated first branch point (1) and a further branch point (3) connected through a decoupling rectifier ($1D_{11}$) to a control conductor (V_1), in that a holding winding of each relay is connected between the associated second branch point (3) connected through a decoupling rectifier ($1D_{11}$) to a control conductor (V_1) and a third branch point (2) connected through a make contact (k_{11}) of the relay to a point of constant potential, and in that the first branch point (1) of each relay is connected to a resistor ($1R_{11}$) the other end of which is adapted to receive a switching-on potential.

2. A system as claimed in claim 1, characterized in that the first branch point (1) of each relay is connected through a decoupling rectifier ($3D_{11}$) to the third point (2) and in that one winding of each relay is included in the system, which winding is connected between the associated second branch point (3) and the third branch point (2).

3. A system as claimed in claim 1, characterized in that the marking and control conductors are actuated by break contacts which apply in the closed state a fixed potential to the relevant conductors.

4. A system as claimed in claim 1, characterized in that the first branch points of the relays are connected through

resistors added to each of the branch points to second control conductors and in that the second control conductors are actuated by marking contacts which apply in the closed state a switching-on potential to the relevant conductors.

5. A relay control system comprising a plurality of relays arranged in a plurality of groups of relays, each relay having an energizing winding and a normally open contact, a separate common marking conductor for each relay group, a plurality of pairs of first and second control conductors, whereby each pair of control conductors corresponds to a separate single relay from each group of relays, a relay control circuit for each relay connected to the corresponding marking, and first and second control conductors, said relay control circuit comprising a holding circuit including the energizing winding and contacts of the respective relay, and first and second alternate holding paths including first and second unilateral conducting devices respectively and extending to the corresponding marking and first control conductors respectively, and an energizing circuit extending from the corresponding second conductor to the corresponding first conductor by way of said energizing winding, said control system further comprising a source of potential having first and second terminals, separate first and second switch means for connecting said marking and first control conductors respectively to said first terminal, and separate third switch means for connecting said second control conductors to said second terminal, whereby an energized relay can be deenergized only when the corresponding first and second switch means are open, and a deenergized relay can be energized only when the corresponding first switch means is open and the corresponding second and third switch means are closed.

6. The control system of claim 5 in which said relay control circuit comprises a series circuit of said first unilateral conducting device, the corresponding energizing

winding, a third unilateral conducting device poled in the same direction as the first unilateral conducting device, and resistor means, connected in that order between the corresponding marking and second control conductors, means connecting said contact between the junction of said energizing winding and a source of potential differing from the potential of said first terminal, and means connecting said second unilateral conducting device between said first control conductor and the junction of said energizing winding and said first unilateral conducting device, said first and second unilateral conducting devices being poled to pass current in the same direction with respect to said winding.

7. The control system of claim 6 in which said relay control circuit further comprises a fourth unilateral conducting device connected between said marking conductor and the junction of said resistor means and third unilateral conducting device, with like polarity electrodes of said third and fourth unilateral conducting devices being connected together.
